UNITED STATES PATENT OFFICE.

EDGAR M. BOTTOME, OF MOUNDSVILLE, WEST VIRGINIA, ASSIGNOR TO FOSTORIA GLASS CO., OF MOUNDSVILLE, WEST VIRGINIA, A CORPORATION OF WEST VIRGINIA.

DESIGN FOR A GOBLET.

Application filed March 14, 1927. Serial No. 21,142. Term of patent 14 years.

To all whom it may concern:

Be it known that I, EDGAR M. BOTTOME, a citizen of the United States, residing at Moundsville, in the county of Marshall and State of West Virginia, have invented a new, original, and ornamental Design for a Goblet, of which the following is a specification, reference being had to the accompanying drawing, forming part thereof.

The figure is a perspective view, showing my new design.

I claim:

The ornamental design for a goblet, as shown.

EDGAR M. BOTTOME.
